UNITED STATES PATENT OFFICE.

ROBERT M. CRITCHFIELD, OF ANDERSON, INDIANA, ASSIGNOR, BY MESNE ASSIGNMENTS, TO DELCO-REMY CORPORATION, OF DAYTON, OHIO, A CORPORATION OF DELAWARE.

SOUND SIGNAL.

Application filed May 28, 1926. Serial No. 112,269.

This invention relates to sound signals and particularly to horns for automotive vehicles.

One object of the present invention is to simplify the construction and to reduce the 5 cost of manufacture of horns of the type in which the diaphragm is vibrated by an electromagnet.

Another object of the present invention is to improve the construction of the magnetic circuit of the electro magnetic motor for operating the diaphragm with the idea of obtaining only such movement of the diaphragm as will be conducive to the production of the best tone.

15 Further objects and advantages of the present invention will be apparent from the following description, reference being had to the accompanying drawings, wherein a preferred form of embodiment of the present 20 invention is clearly shown.

In the drawings:

Fig. 1 is a rear end view of a horn embodying the present invention, the cover enclosing the electromagnet being removed.

25 Figs. 2, 3 and 4 are sectional views taken respectively on the lines 2—2, 3—3 and 4—4 of Fig. 1.

Referring to the drawings, 20 designates a diaphragm which is clamped by screws 21 and nuts 22 between flanges 23 and 24 of diaphragm housing members 25 and 26 respectively. The member 26 provides a collar for supporting a projector 27. The housing member 25 may be described as a cup-shaped member having its end wall 28 provided with an aperture 29.

40 The member 25 provides a frame for supporting an electromagnet, including a magnet frame 31 and a winding 32, and member 25 is made preferably of magnetizable material so as to provide a part of the magnetic circuit of the electromagnet.

Rivets 30 fasten the ends of the U-shaped magnet frame 31 to the end wall 28. The 45 magnet winding 32 is located between insulating discs 33 and 34 upon a magnetizable core 35. The core 35 is provided with an end portion 36 of smaller diameter which extends through a suitable hole in the yoke of the magnet frame 31 and is riveted over at 37 against the rear face of the magnet frame in order to secure the core and winding in position.

The diaphragm is provided centrally with

a hole for receiving a bolt 40 having a circular 55 head 41 and a threaded shank which receives a nut 42. The bolt 40 passes through a magnetizable disc 43, a sleeve 44, one or more shims 45, a washer 46, the diaphragm 20, a washer 47, a tone modifying disc 48 and a lock washer 49. These parts are clamped between the head 41 of bolt 40 and the nut 42. The parts 35, 31, 28, 43, 40 and 41 are magnetizable and therefore provide a magnetic circuit for the flux produced by current flowing through the coil 32.

The circuit breaker for controlling the flow of current to the coil 32 in response to movements of the disc or armature 43 includes contacts 50 and 51. Contact 50 is 70 carried by and is electrically connected with a U-shaped spring conductor or contact bracket 52 which is in electrical contact with a terminal clip 53 having an apertured ear 54. The contact 51 is carried by and is electrical- 75 ly connected with a bracket 55 having its middle portion 56 offset from its end portions 57. The bracket 55 includes an apertured ear 58. The parts 52, 53 and 55 are secured by rivets 59 to a bracket 60. The part 55 80 is insulated from the parts 53 and 52 and all of these parts are insulated from the bracket 60 by an insulating plate 61 and insulating bushings 63 which surround the rivets 59. The bracket 60 is fastened to the end wall 28 85 of the housing 25 by rivets 62. The free end 63 of the bracket 60 is provided with a plain hole for receiving a screw 64, which is threaded into a nut 65. The bracket is bent to provide a shoulder 66 which engages one of the 90 flat sides of the nut 65 to prevent it from turning when the screw 64 is turned. The screw 64 passes through a hole 67 in the end wall 28 and is provided with a head 68 located rearwardly of said wall 28. The head 68 of the 95 screw 64 is provided with radially extending serrations 69 which cooperate with correspondingly formed serrations 70 provided by the end wall 28. The bracket 60 is composed of resilient sheet material and yieldingly 100 maintains the serrations 69 and 70 in engagement to prevent accidental turning of the screw 68. The contact bracket 52 carries adjacent its free end a non-conducting button 71 adapted to be engaged by the armature disc 43. By turning the screw 64, the bracket 60 is moved relative to the wall 28, hence the button 71 is moved relative to the armature

43. In this manner the instant of contact separation relative to the movement of the armature 43 may be adjusted.

As shown in Fig. 1, the housing end wall 28 is provided with a notch 72 for receiving the spring conductor 52 so that the button 71 may be located in the space between the armature 43 and the electromagnet. One of the leads 73 of the coil 32 is connected with the ear 58 of the bracket 55. The other coil lead 74 is connected with a terminal bolt 75 which is insulatingly supported by the side wall of the diaphragm housing 25. The ear 54 of the terminal clip 53, which is connected with contact 50, is connected by a wire 76 with a terminal bolt 77 which is also insulatingly supported by the housing 25. Sparking of the contacts 50 and 51 is reduced by a condenser 80 having its leads 81 and 82 connected with brackets 55 and 53 respectively. The condenser 80 is attached to a bracket 83 which is secured by a screw 84 to the rear surface of the housing end wall 28.

When current flows through the coil 32 the magnetic circuit will be energized and the armature 43 will be attracted toward the core 35 in order to flex the diaphragm 20 rearwardly as viewed in Fig. 2. During rearward movement of the disc 43 the button 71 will be engaged by it, and the contact 50 will be separated from the contact 51 in order to interrupt the circuit of the coil 32. When this interruption occurs the diaphragm 20 will move forwardly due to its own resiliency, and the spring conductor 52 will be released to permit the contact 50 to re-engage the contact 51. These operations will be repeated as long as the terminals 75 and 77 are connected with a current source.

40 The electromagnet is enclosed by a cup-shaped cover 90 having its circular edge 91 received by an annular shoulder 92 provided by the housing 25. The cover 90 is secured in position by a screw 93 passing through a central hole in the cover 90 and received by a tapped hole 94 in the core 35.

For the production of the best tone it is essential that the force setting the diaphragm in motion act in a direction substantially parallel to the axis of the diaphragm so that the portion of the diaphragm to which the actuating member is attached will vibrate in a direction which is perpendicular to the plane of the diaphragm.

55 Vibration perpendicular to the plane of the diaphragm is substantially always assured as long as the air gap between the members 28 and 43 remains uniform at all points. However, if for any reason, one portion of the member 43 is brought into closer relation with the member 28 than other portions thereof, a reduced air gap obtains, at which area there would be a concentration of magnetic lines of force. Such concentration results in a greater pull on one side of the mov-

able member than on the other, which in the present instance, would cause tilting of the armature and its member 43 resulting in what might be termed "cocking" of the diaphragm, or more specifically would cause the vibrations of said diaphragm to be out of the perpendicular to the plane thereof. Such action tends to move the armature out of proper axial alignment with the core 35 which type of vibration would result in a rough tone.

To eliminate such "cocking" of the diaphragm when the air gap between members 28 and 43 is not uniform, the adjacent surfaces of the core and armature have been so shaped that the magnetic lines of force, passing between said core member and armature member, are concentrated substantially within a portion of the air gap between them. This portion on which the flux is concentrated is preferably coaxial or concentric with the diaphragm, and is provided preferably by providing at least one of the members with a convex or protuberant surface. This portion tends to maintain the armature coaxial with the core and resists the tendency of the armature to move out of coaxial relation with said core. The area of the gap between members 35 and 41 is much less than the area of the gap between members 28 and 43. Hence the magnetic pull per unit of area will increase more rapidly between the core and the armature than at the gap between members 28 and 43, as the armature approaches the core. Therefore, the tendency of the armature to remain coaxial with the core increases as the armature approaches the core and the cocking of the diaphragm will be even less at the end of its movement toward the core, than at the beginning of its movement.

One advantage of the present invention therefore results from the feature of providing means which will automatically compensate for variations in air gaps of the magnetic circuit, so that extreme care in manufacture is not necessary to produce satisfactory operation of the sound signal.

Another advantage resulting from the present construction is that the horn may be inspected while operating, in order to determine what adjustments should be made to cause the horn to perform according to a certain standard. The air gaps, particularly the narrower one between the parts 35 and 41, are located so that thin metal plates may be inserted through the notch 72 and between the parts defining the gaps in order to determine, while the horn is assembled, whether the gaps are of the correct width. The circuit breaker also may be inspected through the notch 72.

While the form of embodiment of the present invention as herein disclosed, constitutes a preferred form, it is to be understood that other forms might be adopted, all coming within the scope of the claims which follow.

What is claimed is as follows:

1. A sound signal comprising in combination, a housing; a diaphragm secured to the housing; an electromagnet including a winding and a core attached to the housing; an armature carried by the diaphragm coaxially with respect to the core and presenting an end surface adjacent a surface of the core, said surfaces being so formed relatively to each other that the lines of magnetic flux passing between the core and armature are concentrated within a region coaxial with respect to the axes of the diaphragm and core; and a circuit interrupter for controlling the electromagnet. 50
2. A sound signal comprising in combination, a housing; a diaphragm secured to the housing; an electromagnet including a winding and a core attached to the housing; an armature carried by the diaphragm coaxially with respect to the core and presenting an end surface adjacent a surface of the core, one of said surfaces being convex so that the lines of magnetic flux, passing between the core and the armature, are concentrated within a region coaxial with respect to the point of closest approach of the armature and core lying in their mutual axis; and a circuit interrupter for controlling the electromagnet. 55
3. A sound signal comprising in combination, a housing; a diaphragm secured to the housing; an electromagnet including a winding and a core attached to the housing, the core presenting a substantially flat end surface; an armature carried by the diaphragm coaxially with respect to the core and presenting a convex end surface adjacent the flat end surface of the core so that the lines of magnetic flux, passing between the core and the armature, are concentrated within a region coaxial with respect to the point of closest approach of the armature and core lying in their mutual axis; and a circuit interrupter for controlling the electromagnet. 60
4. A signal device comprising in combination, a frame including an apertured, magnetic plate; an electromagnet frame mounted on said plate; a core supported by said frame and magnetically connected with the plate and having a surface facing the aperture in the plate; a winding about the core; a diaphragm supported by the frame, in spaced relation to the plate; an armature carried by the diaphragm so as to be coaxial of the core and so that one surface thereof lies adjacent the surface of the core facing the aperture in the plate, one of said adjacent surfaces being provided with a protuberant portion adjacent the inner surface, to concentrate the magnetic flux passing from one to the other within a region concentric with respect to the mutual axis of the core and armature; and a magnetizable flange extending from the armature beyond the edge of but in spaced relation to the aperture in the plate. 65
5. A signal device comprising in combination, a frame including an apertured, magnetic plate; an electromagnet frame mounted on said plate; a core supported by said frame and magnetically connected with the plate so that the flat, end surface of the core is held adjacent the aperture in the plate; a winding about the core; a diaphragm supported by the frame, in spaced relation with and parallel to the plate; an armature carried by the diaphragm so as to be coaxial of the core, said armature having a protuberent surface portion held adjacent to, but in spaced relation with the surface of the core by the diaphragm, to concentrate the magnetic flux passing from one to the other within a region concentric with respect to their mutual axis; and an annular magnetic flange provided on the armature, said flange being greater in transverse dimension than the aperture in the plate so as to extend beyond the edges of said aperture and overlie an annular ring portion of the plate, said flange being maintained in spaced relation to the plate to provide an air gap between said flange and plate, greater in area than the air gap between the adjacent surfaces of the core and armature. 70
